UNITED STATES PATENT OFFICE.

WILLIAM STEPHENSON, OF MORRIS, CANADA.

SCRAPER FOR SEED-DRILLS.

SPECIFICATION forming part of Letters Patent No. 691,016, dated January 14, 1902.

Application filed December 15, 1900. Serial No. 39,948. (No model.)

To all whom it may concern:

Be it known that I, WILLIAM STEPHENSON, a citizen of the Dominion of Canada, and a resident of Morris, in the county of Provencher, Province of Manitoba, Canada, residing temporarily at St. Louis Park, Minneapolis, in the county of Hennepin, in the State of Minnesota, have invented a certain new and useful Improvement in Scrapers for Seed-Drills; and I do hereby declare that the following is a full, clear, and exact description of the construction and operation of the same.

The object of the device is to further improve the seed-drill scrapers in addition to those already patented by me; and the present invention relates more particularly to an improved form of the scraper which is made to operate between the disks of the drill-shoe and which consists in forming the center scraper or the one working between the disks convex on the outside and concave on the inside in order to work more smoothly in that position and prevent the frictional noise when in operation, which was more or less objectionable in my old method of construction. By my present improved construction of the form of the said center scraper its edges impinge on the inside of the disks at a different angle as it does when straight across and renders the device nearly noiseless, if not absolutely so, a condition to be greatly desired.

By reference being made to the accompanying drawings, forming part of this specification, Figure 1 represents a side view of a seed-drill frame and spout with the disks removed. Fig. 2 is a rear elevation with disks attached and center scraper between them. Fig. 3 is a rear view of center scraper detached from the disks. Fig. 4 is a cross-section of the center scraper.

In the drawings, A A represent two disks attached to the axles of the grain-spout and frame B, the rear part a of the said frame projecting backward, terminating in a curve b, with a projection c on the inside, through which a hole d is made and screw-threaded

to receive the screw-bolt f, which secures the center scraper to the frame.

C is the center scraper, formed convex on the outside and concave on the inside, as shown at Figs. 3 and 4, and slightly tapering on the sides downward to fit the space between the disks A. A vertical slot g is formed in the said scraper C for a screw-bolt f to pass through and into the hole d. When the scraper is placed on the rear end of the frame a and tightened, a washer h is interposed between the head of the screw and the scraper, and the elongation of the slot g allows the scraper to be adjusted vertically to impinge on the disks A and take up the wear of the scraper when necessary. As the edges of the said scraper, being convex, do not impinge at right angles on the disks, the frictional noise is thereby prevented that would otherwise be caused if the edges of the scraper impinged at right angles on the disks.

Having thus described my device and its advantages, what I claim as my invention is—

1. In combination with the disks of a seed-drill shoe, a center scraper constructed of concavo-convex form, and secured between the disks, whereby the edges of the center scraper impinge on the disks at an angle to prevent noise.

2. In combination with the disks of a seed-drill shoe, a curved center scraper C, formed concavo-convex with a vertical slot g, formed therein and secured to the corresponding curved frame a, b, of the grain-spout of a seed-drill by a projection c, having hole d, screw-threaded to receive bolt f to operate between the disks to keep the inside faces of the disks free from soil and operate smoothly without noise substantially as specified.

Dated at Minneapolis, Minnesota, the 20th day of October, 1900.

WILLIAM STEPHENSON.
In presence of—

DWIGHT EDMOND MERCHANT,
GEORGE FRANK MOSELEY.
